(57) **CLAIM**

The ornamental design for a toy, as shown and described.

DESCRIPTION

FIG. 1 is a front view of a toy, showing our new design; FIG. 2 is a rear view thereof; FIG. 3 is a left side view thereof, the opposite side being a mirror image;

FIG. 4 is a top view thereof;

FIG. 5 is a bottom view thereof;

FIG. 6 is a perspective view thereof; and,

FIG. 7 is a perspective view thereof with the toy in a separated position.

The parts shown by means of broken lines and colored in white are not part of the claimed design.
